Primary Examiner — Kevin K Rudzinski*Assistant Examiner* — Paul D Bohannon(74) *Attorney, Agent, or Firm* — Dority & Manning, P.A.(57) **CLAIM**

The ornamental design for a lighting fixture, as shown and described.

DESCRIPTION

FIG. 1 is a perspective view of a lighting fixture;
 FIG. 2 is a top view of a lighting fixture;
 FIG. 3 is a bottom view of a lighting fixture;
 FIG. 4 is a side elevation view of a lighting fixture;
 FIG. 5 is a side elevation view of a lighting fixture;
 FIG. 6 is a side elevation view of a lighting fixture; and,
 FIG. 7 is a side elevation view of a lighting fixture.
 The broken line showing of portions of the lighting fixture is included for illustrating environmental aspects only and form no part of the claimed design.
